(57) **CLAIM**

The ornamental design for a handle of the dental floss holder, as shown and described.

DESCRIPTION

FIG. 1 is a perspective view of a handle of the dental flosser holder, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the handle of the dental flosser holder are for environmental illustrations and do not form part of the claimed design.
